LOCOMOTIVE BOILER

Walter H. Hinsch and John Baker, Chicago, Ill.,
assignors to Locomotive Firebox Company,
Chicago, Ill., a Corporation of Delaware

Application April 16, 1931. Serial No. 530,520

4 Claims. (Cl. 122—466)

This invention relates to improvements in locomotive boilers and it consists of the matters hereinafter described and more particularly pointed out in the appended claims.

5 The conventional locomotive boiler includes a barrel having a firebox at one end and a smoke box at the other, with the fire tubes or flues extending between said boxes and passing through the single compartment for both the water and steam. While greater power has been obtained by increasing boiler dimensions, certain factors are present which limit the size of the same. However, power demands have increased and these must be met without further enlarging sizes 10 which have reached a practical limit because with longer barrels, longer tubes are necessary and these all increase the cost without a proportionate power value.

20 Many of such boilers are equipped with superheaters in the form of return bend tubes disposed in the forward or smoke box end of the top tiers of tubes which must be enlarged in diameter to receive the superheater tubes.

25 While such superheater tubes are effective to a certain extent so far as increased efficiency is concerned, they require frequent attention that must withdraw the locomotive from service. The flues in which such superheater tubes are disposed, are prone to plug up and the superheater tubes themselves quickly deteriorate under the 30 abrasive action of the products of combustion. Again, such superheater tubes being disposed in the smoke box end of the flues, remote from the firebox ends, only the rear end part of the superheater tubes are in that zone wherein gas or 35 combustion products temperature is higher than superheat temperature with the result that the front ends of such tubes give up their heat to said gases or products of combustion with a reduction of temperature in that end desired to 40 have the highest temperature. In other words, with the present type of superheaters, less than half of the superheating surface is effective for 45 its intended purpose.

In the relatively long boiler, wherein both 50 boiler water and generated steam are contained in the same compartment, to provide an efficient generation of steam, the entire water content must be kept in circulation both fore and aft to equalize the temperature of the entire body of water otherwise a fluctuation in steam generation 55 will result and quiet areas develop in the boiler which are favorable to muddy deposits with the objectionable effects well known.

Among the many objects of our invention is to provide a boiler wherein power is not so dependent upon enormous sizes but is more dependent upon positioning the parts thereof wherein they are more effective to produce the desired results and at the same time keep the cost within reason.

Another object of our invention is to provide a boiler of this kind arranged in sections or compartments whereby it is not necessary to heat 65 the entire water content of the boiler through circulation, but only a small part or amount thereof so that steam generation will be more efficient and as this water is diminished due to such steam generation, it is replenished so as to 70 keep this amount constant from another boiler compartment containing feed water that is heated to proper feeding temperature by gases and combustion products having temperatures 75 reduced by such steam generation.

Still a further object of the invention is to provide a boiler of this kind which includes a superheater compartment located in a part of the boiler whereby greater superheater efficiency is attained without sacrificing steam generating efficiency and at the same time permits of taking off such superheated steam at a point closer to its point of actual use in the cylinders and which point in this instance is at 80 the bottom of the boiler.

Still another object of our invention is to provide a boiler of this kind made in a plurality of sections comprising steam generating, steam superheating and feed water heating compartments, in the order named and whereby sheets 85 and tubes of lesser length than now used may be employed with a greater factor in strength and safety.

The above mentioned objects of the invention as well as others, together with the many advantages thereof, will more fully appear as we proceed with our specification.

In the drawings:—

Fig. 1 is a longitudinal central section through all but the smoke box or front end of a locomotive boiler embodying our invention.

Figs. 2, 3 and 4 are transverse vertical sectional views through the boiler as taken on the lines 2—2, 3—3 and 4—4 respectively of Fig. 1.

Fig. 5 is a longitudinal vertical sectional view on an enlarged scale of the mid portion of the improved boiler and illustrates more specifically the superheater compartment and the adjacent ends of the steam generating and feed water heating compartments.

In general, our improved locomotive boiler is of the conventional shape and includes the usual, horizontally disposed cylindrical boiler shell formed therein with associated flue sheets to divide the shell as a whole into a steam generating compartment, a superheater compartment, and a feed water heating compartment in the order named.

In the steam generating compartment is the usual firebox and at the front end of the boiler is the usual smoke box. Fire tubes are provided in the various compartments for the passage of the products of combustion. As the steam is generated it passes to the superheater compartment where it must follow a tortuous or zig zag path before passing to the cylinders for use under the control of the throttle valve. Thus the water is acted upon by those parts of highest temperature to generate the same into steam, and the steam is superheated by the products of combustion at that point wherein said products have not as yet lowered to that temperature lower than the steam. Thereafter these products which are now incapable of generating steam and superheating the same are employed for feed water heating whereby every heat unit performs its function so that not only is the highest boiler efficiency attained but a corresponding saving in fuel is likewise attained.

Referring now in detail to that embodiment of the invention illustrated in the drawings and especially to Fig. 1 thereof, 1 indicates as a whole the tubular shell of the boiler made up of a plurality of sections 2, 3 and 4 respectively to provide a steam generating compartment 5 at the rear end of the shell, a second and superheater compartment 6 forward thereof and a feed water heating compartment 7 forward of said superheating compartment, a smoke box 8 being joined to the front end of the shell in the usual manner.

Centrally of the top of the smoke box is a stack 9 and at the bottom of the smoke box and connected thereto as by the usual saddle are the cylinders 10 and steam chests 11 respectively. The compartments 5 and 6 are separated by longitudinally spaced flue sheets 12 and 13 respectively defining a chamber 14 while the compartments 6 and 7 are separated by longitudinally spaced flue sheets 15 and 16 respectively, defining a chamber 17 and the feed water heating compartment is separated from the smoke box by a flue sheet 8^a. To the top of the boiler shell above the compartment 14 is secured a dome 18 and the shell is provided with openings 19 under the dome whereby steam may pass from the generating compartment into the superheating compartment as is best shown by the arrows in Fig. 5. Suitably arranged in the shell in the plane of the chamber 14 is a manhole and cover 20. The top of the shell above the chamber 17 is provided with a manhole 21 and associated shallow dome 22 adapted to receive a cover that is not shown. By means of said manholes and covers, a workman may enter the chambers when so necessary.

In the steam generating compartment 5 is located a firebox 23 including a front flue sheet 24, a rear sheet 25, a crown sheet 26 and the usual side sheets and these various sheets coact with associated sheets of the shell to provide the usual side water legs (not shown) and the front and rear water legs 27 and 28 respectively all communicating with said compartment 5 in the usual manner and bottomed by the mud ring 29. In the firebox is located one or more wa-

ter steaming and circulating elements 30, having an elongated flat hollow top discharge end that opens through the crown sheet 26 and a tubular inlet neck 31 that opens through that bottom part of the flue sheet 24 that forms one of the walls of the front water leg or throat 27. Connecting the flue sheets 12 and 24 is a nest of relatively short fire tubes or flues 32, the height of which nest is determined by the height of the flue sheet 24.

Connecting the flue sheets 16 and 8^a respectively and disposed in the compartment 7 is a nest of relatively short fire tubes or flues 33 and which nest is of a height greater than that of the nest of tubes 32 in the compartment 5. In the compartment 6 is provided a nest of fire tubes or flues 34 connected at their ends in the flue sheets 13 and 15 respectively. Preferably these tubes are of a diameter less than that of the tubes 33 and are disposed in alignment therewith so that should it ever be necessary to remove and replace any of said tubes 34, the same may be done through the tubes 33 from the smoke box end of the boiler.

In the compartment 6 is located a plurality of vertically spaced baffle plates 35, alternate ones of which are fixed at one end to the flue sheet 13 and are spaced at their other end from the flue sheet 15 while the intermediate ones are fixed at one end to the flue sheet 15 and are spaced at their other ends from the flue sheet 13. As shown these baffles provide a tortuous back and forth passage through the compartment 5 with the saturated steam entering the compartment from the rear end at the top and with the superheated steam leaving said compartment from the front end at the bottom. To the bottom front end of this compartment is connected the rear end of a steam pipe 36 which extends forwardly and is there provided with branches 38 which in turn are connected to the steam chests 11-11. Entrance of steam into the branches is controlled by a throttle valve 39 which as is apparent is disposed outside the boiler instead of inside of the same as is heretofore customary.

At the forward end of the feed water heating compartment at the top of the shell is formed a top injector flange 40 whereby water may be fed into the feed water heating compartment 7 and connecting said compartment with the steam generating compartment at one side of the boiler is a conduit 41 in which is interposed a feed pump 42 whereby heated feed water may be transferred as required from the compartment 7 into the compartment 5 against the relatively high pressure therein.

In the operation of the boiler thus far described, and with a level of water in the compartment 5 of sufficient height to cover the crown sheet, it is apparent that the body of water therein is relatively small in comparison to that wherein the entire shell comprises both the water containing and steam generating chamber. It is further apparent that this small body is more rapidly and efficiently heated for the generation of steam not only by the firebox sheets but also by the flues 32. Thus water heating and steaming generating action is materially increased by the syphonic action of the elements 30 which increases the circulation of water in said compartment by withdrawing it from the bottom of the compartment and discharging it into the top of said compartment above the crown sheet. Thus by operating upon a relatively small body of water at a time, the steam generating capacity 150

is greatly increased and fuel consumption is reduced in proportion.

As the products of combustion leave the firebox, they enter and pass through the flues 5 into the chamber 14 and from there enter the tubes 34 to pass into the chamber 17. From this last mentioned chamber they enter the tubes 33 and pass into the smoke box to be discharged up the stack 9 in the usual manner.

10 The steam generated in the compartment 5 passes through the openings 19 beneath the dome 18, into the compartment 6 where it is caused to follow a tortuous or zig zag path fore and aft, through the nest of tubes 34 therein and as the 15 products of combustion passing through said tubes are at a relatively high temperature, such steam is superheated before it enters the pipe 36 on its way to the cylinders 10. Of course, after these products have given up a part of their heat 20 units in the superheating of the steam in the compartment 6, they pass into the tubes 33 to be discharged into the smoke box. However, in their passage through these tubes, they give up more heat units in the heating of the feed water but 25 by the time they have reached these tubes, they are reduced to that temperature wherein they are incapable of steam generation.

As the water diminishes in the compartment 5 due to its generation into steam, the feed pump 30 42 is started into operation to pump heated feed water into said compartment 5 but as this water is at relatively high temperature its introduction into the compartment 5 in no way chills the same to that extent that makes the generation of steam erratic. Thus a full head of steam without power 35 loss can be maintained.

Thus in the improved boiler the various compartments are so relatively located with respect to gas (or products of combustion) temperatures as to create a maximum thermal head with a corresponding increase in the extraction of the heat units offered to the boiler. Thus feed water comes into contact with heating surfaces receiving the lowest flue gas temperatures in a forward compartment whereas steam generation and superheating takes place at the rear end of the boiler where the highest flue gas temperatures exist. This arrangement is advantageous as it maintains the greatest thermal head of heat transfer from gases through the various sheets and flues to the water and steam.

By arranging the superheater chamber in a close proximity to the firebox, it is possible to so design or form the heating surfaces as to extract additional heat from the gases by maintaining greater variation between the heat giving and heat receiving elements throughout the entire boiler to the foremost flue sheet and therefore in no instance, does a condition arise when the water or steam is giving off heat to the flue gases. Thereby the boiler is possible of a greater thermal heat which increases boiler efficiencies and a higher degree of superheat.

By the arrangement described, many other advantages are obtained and among these is the omission of the usual superheater units with additional weight, first costs and the usual maintenance. Again, it makes possible the practical use of tubes of smaller diameter and length which is advantageous both for construction purposes and higher evaporation value.

The construction is more simple and is readily adapted to present boilers with an economy of construction and furthermore, shorter barrel sections may be used and these are butt welded to-

gether in the planes of the chambers 14 and 17 where no appreciable high interior pressures exist.

No inside throttles are required and it is not necessary to open up the front end with the usual disturbance of draft appliances as is required in boilers having the present type of superheater wherein the superheater tubes are disposed in the flues and the heads are disposed in the smoke box. Again, by use of a relatively short generating compartment, the water level therein is not so greatly disturbed or changed in ascending or descending a grade whereby danger of uncovering or exposing the crown sheet above the water level is minimized.

By the use of short flues many structural advantages are attained both in strength and heat transmission qualities and in long boilers, combustion chambers need not be resorted to. With a reduced volume of water to be operated upon, steam may be raised much faster than in a single compartment boiler. It is also pointed out that by reason of the chamber mentioned between the nests of flues, the larger particles of the products of combustion are broken up into substantially fine particles and are cooled to an extent which prohibits the starting of wayside fire due to the ejection of live sparks up the stack.

While in describing the invention, we have referred in detail to the form, arrangement and construction of the various correlated parts, the same is to be considered merely as illustrative of one embodiment of the invention so that we do not wish to be limited thereto except as may be specifically set forth in the appended claims.

We claim as our invention:—

1. A locomotive boiler embodying therein a boiler shell formed to provide longitudinally spaced steam generating, steam superheating and feed water heating compartments respectively with chambers therebetween, a smoke box associated with one end of the feed water heating compartment, a firebox arranged in said steam generating compartment and including a flue sheet and means providing for the passage of the products of combustion from the firebox to the smoke box and including sets of flues in said steam generating, superheating and feed water heating compartments respectively, the flues in the superheating compartment being of a diameter less than those in the feed water heating compartment and arranged in line therewith.

2. A locomotive boiler embodying therein, a boiler shell, a flue sheet at the front end thereof, a firebox at the rear end thereof and including a flue sheet, means providing pairs of longitudinally spaced flue sheets between said flue sheet at the forward end of the shell and said firebox flue sheet which flue sheets define a steam generating compartment, a superheating compartment and a feed water heating compartment with chambers therebetween and sets of flues disposed in the various compartments and secured at their ends in said flue sheets the flues in said superheating compartment being in line with and smaller in diameter than the flues in one of the other compartments.

3. A locomotive boiler embodying therein a boiler shell formed to provide a plurality of longitudinally spaced, end and intermediate compartments, with chambers therebetween, a smoke box associated with one end of one of the end compartments, a firebox arranged in the other end compartment and including a flue sheet, and means providing for the passage of the products of combustion from the firebox to the

smoke box and including sets of flues in said end and intermediate compartments, the flues in the intermediate compartment being of a diameter less than those in one of said end compartments and arranged in line therewith.

4. A locomotive boiler embodying therein a boiler shell formed to provide a plurality of longitudinally spaced front, intermediate and rear end compartments with chambers therebetween,
